UNITED STATES PATENT OFFICE.

WILLIAM MARSHALL AND EDGARD C. DE SMET, OF DETROIT, MICHIGAN, ASSIGNEES TO
BRIGGS MANUFACTURING COMPANY, OF DETROIT, MICHIGAN, A CORPORATION OF
MICHIGAN.

DOOR LOCK.

Original application filed July 19, 1926, Serial No. 123,535. Divided and this application filed July 5, 1927.
Serial No. 203,439.

This invention relates generally to fasteners or latches designed particularly for use with vehicle doors and consists in certain novel features of construction, combinations and arrangements of parts as will be more fully described and particularly pointed out in the appended claims.

In the accompanying drawings:

Figure 1 is a horizontal sectional view through a door with our fastening means applied thereto;

Figure 2 is a side elevation of the outer latch assembly showing the reciprocating dogging means in its operative position;

Figure 3 is a view similar to Figure 2 showing the dogging means in its inoperative position;

Figure 4 is a vertical sectional view through the outer lock assembly;

Figure 5 is a detail perspective view of the locking slide.

Referring now to the drawings, the numeral 1 designates a door preferably of a vehicle body, having a pillar 2 that is connected at its inner and outer edges to suitable sheet metal panels 3 and 4 respectively, and which supports a channel-shaped strip 5, constituting a runway for a vertically movable glass window panel 6. As shown, the pillar 2 is preferably constructed of sheet metal and is substantially Z-shaped in cross section, while the strip 5 is also constructed of sheet metal and holds a suitable channel-shaped felt guide 7 for the window panel.

With such an arrangement of parts, wherein the pillar 2 has a very small cross section, the occupants of the vehicle will have an increased vision and a wider glass panel may be employed than that used in the ordinary type of door constructions. However, it is necessary to provide a particular type of latch mechanism for use with such a door construction and, in the present instance, we provide an inner latch assembly designated at 8, which is mounted upon the panel 3, while an outside latch assembly 9 is mounted upon the outer panel 4. Both of these assemblies are connected to and operate a latching bolt 10 which preferably straddles the guideway for the vertically movable glass panel 6.

The inner latch assembly 8 and the specific construction of the latching bolt 10 will not

be described herein as they form the subject matter of our co-pending application Serial No. 123,535 filed July 19, 1926, the present case being a division thereof.

Referring now to Figures 2 and 3 in which the outer latch assembly 9 is shown, there is provided an outer case plate 11 secured to the outer panel 4 in any suitable manner and to which a cover plate 12 is spaced therefrom and secured thereto by means of suitable flanged portions 13. Located between 65 and having its end portions journaled in suitable openings in the case plate and cover plate is a hub member 14 provided with a squared opening to receive the shank 15 of an outer handle 16.

Rigidly mounted upon the hub 14 and adapted to turn therewith in a rearwardly direction is a roll back 17 normally abutting against a struck-up projection 18 of the case plate and held against the same by means 75 of a spring 19 suitably mounted upon the case plate 11.

Rigidly mounted upon the outer end portion of the rollback 17 is a lug 20 which is detachably connected to the rear end portion 80 of a link 21, the forward portion of the link being connected to the outer end of the latching bolt 10.

It will be apparent that by turning the handle 16 in a rearwardly direction, the roll back 17 together with the link 21 will be moved rearwardly, retracting the locking bolt 10.

For locking the handle 16 against rotary movement, we provide a slide 22, the upper 90 portion of which is interposed between the cover plate and roll back. This slide is provided at its upper end with an elongated opening 23 straddling the hub 14, while directly below the opening 23 is a struck-out 95 portion 24 which is adapted to engage a projection 25 upon the lower end of the roll back when the slide is in its upper position. A spring arm 26 is secured to the inside portion of the slide and is adapted to 100 move therewith. As shown, this spring is designed to enter a depressed portion 27 in the case plate when the struck-out portion 24 engages the projection 25 on the roll back.

Preferably the lower end portion of the 105 slide 22 is enlarged as at 28 and is provided with a transversely extending slot 29 for receiving an eccentrically mounted stud 30

of a standard lock mechanism 31. The lower edge of the slide 22 is provided with an inturned flange 32, which is slotted on both sides thereof as at 33, to engage the edges of an opening 34 located in the lower portion of the case plate 11.

For securing the lock mechanism in place, there is provided a housing 35 having a portion 36 spaced from and extending substantially parallel to the case plate 11. The housing 35 is provided with the flanged portions 37 extending from the spaced portion 36 and secured to the case plate in any suitable manner, while both the case plate and portion 36 are provided with aligned openings for receiving the lock mechanism 31.

With the slide in its lower position the roll back will be free to move in a rearwardly direction. However when the stud 30 of the lock mechanism 31 is rotated, the slide will be moved into its upper position whereupon the struck-out portion 24 will engage the projection 25 of the roll back and prevent any rearward movement of the same.

While it is believed that from the foregoing description the nature and advantage of our invention will be readily apparent, we desire to have it understood that we do not limit ourselves to the specific construction herein shown and described, and that such changes may be resorted to when desired as fall within the scope of what is claimed.

What we claim as our invention is:

1. In a latch mechanism, the combination with a case plate, and a roll-back on the case plate having a hub and a projection, of dogging means for said roll-back including a key controlled eccentric on the case plate in spaced relation to the roll-back, and dog carrying and operating means between said eccentric and roll-back including a recipro-

cating element having slots receiving said roll-back hub and eccentric and having a projection engageable with the projection of said roll-back. 45

2. In a latch mechanism, the combination with a case plate, and a roll-back on the case plate having a hub and a projection, of 50 dogging means for said roll-back including a key controlled eccentric on the case plate in spaced relation to the roll-back, a reciprocating element bridging the space between said eccentric and roll-back, having a longitudinally extending slot receiving the roll-back hub and having a transversely extending slot receiving said eccentric, and a projection on said element intermediate of said slots engageable with the roll-back projection aforesaid upon reciprocation of said element. 55

3. In a latch mechanism, the combination with a case plate, and a roll-back on the case plate having a hub and a projection, of 60 dogging means for said roll-back including a key controlled eccentric on the case plate in spaced relation to said roll-back, a reciprocating element having a longitudinally extending slot receiving said roll-back hub 65 whereby said element may be guided by said hub, having a transversely extending slot receiving said eccentric whereby said element may be reciprocated by said eccentric, having a projection engageable with said roll-back projection when said element is reciprocated whereby said roll-back may be rendered inoperative, and a spring between said case plate and element retarding the movement of said element and serving to 70 hold the same in adjusted position in respect to said case plate and against rattling. 75

In testimony whereof we affix our signatures.

WILLIAM MARSHALL.
EDGARD C. DE SMET.
